UNITED STATES PATENT OFFICE.

ERIC A. LINDQUIST, OF MIDDLETOWN, CONNECTICUT, ASSIGNOR TO W. & B. DOUGLAS,
OF MIDDLETOWN, CONNECTICUT, A CORPORATION OF CONNECTICUT.

DESIGN FOR A PUMP-HOUSING.

46,774.

Specification for Design.

Patented Dec. 15, 1914.

Application filed September 23, 1914. Serial No. 863,234. Term of patent 3½ years.

To all whom it may concern:

Be it known that I, ERIC A. LINDQUIST, a citizen of the United States, and a resident of Middletown, in the county of Middlesex, State of Connecticut, have invented a new, original, and ornamental Design for a Pump-Housing, of which the following is a specification, reference being had to the accompanying drawing, forming part hereof.

The invention is shown in perspective view in the accompanying drawing.

I claim:

The ornamental design for a pump housing as shown.

ERIC A. LINDQUIST.

Witnesses:

MAUDE KIRBY,

H. C. MORGAN.
